UNITED STATES PATENT OFFICE.

HARRY W. DENHARD, OF SAN FRANCISCO, CALIFORNIA, ASSIGNOR TO THE CUTLER-HAMMER MFG. CO., OF MILWAUKEE, WISCONSIN, A CORPORATION OF WISCONSIN.

ELECTRIC HEATING DEVICE.

1,101,527.

Specification of Letters Patent. Patented June 30, 1914.

Application filed October 31, 1911. Serial No. 657,811.

To all whom it may concern:

Be it known that I, HARRY W. DENHARD, a citizen of the United States, residing at San Francisco, in the county of San Francisco and State of California, have invented new and useful Improvements in Electric Heating Devices, of which the following is a full, clear, concise, and exact description, reference being had to the accompanying 10 drawing, forming a part of this specification.

My invention relates to electric heating devices.

It has among its objects to provide an improved electric heating device.

15 A further object of my invention is to provide an improved electric heating device wherein the supply of current through the device is automatically controlled by the object to be heated.

20 A further object of my invention is to provide an improved electric heating device of this type which is especially adapted to use as an electric tool or curling iron heater, an automatic switch device being employed 25 to cut the heater in or out of circuit when the tool or other device is inserted in the heater.

Other objects and advantages of my improved construction will hereinafter appear.

30 In the accompanying drawings I have for purposes of illustration shown one form which my invention may assume in practice. My invention is not, however, limited to this form, but may assume other forms.

35 In the views of these drawings: Figure 1 shows a central sectional view through the device. Fig. 2 shows an end elevation of the device. Fig. 3 shows a diagrammatic view of the circuit connections.

40 In the construction shown in the drawings for purposes of illustration, I have illustrated a casing 1 mounted upon a base 2 and having a central chamber 3 arranged to receive the object to be heated 4; a resistance 45 material 5 being wound around the heating chamber, and the current supply to this resistance material being controlled by a snap switch mechanism 7 actuated by the movement of a door 8 of the chamber 3.

50 The casing 1 is preferably formed of stamped sheet metal, and as shown in Fig. 2 preferably has a substantially cylindrical cross-section. As illustrated in Fig. 1 it preferably includes an inner metal sleeve 9

held in central position within the casing by 55 means of end members 10 and 11, which are attached by means of suitable screws 12 and 13 to the outer casing 1. In a preferred form the end members 10 and 11 preferably project into the ends of the sleeve 9, the end 60 member 10 closing this end of the sleeve, while the end member 11 is provided with a flange which encircles the mouth of the sleeve. In a preferred form the casing 1 is spaced from the sleeve 9 a suitable distance 65 and is so constructed as to form a sealed heat retaining chamber 14 surrounding the sleeve 9. In a preferred form a bottom strip 15 is arranged beneath the underside of the casing 1. This bottom strip 15 70 is preferably so arranged as to extend at an angle of substantially 30 degrees with respect to the base member 2, so that the article to be heated may be more readily inserted, and is supported in this 75 position by means of a depending supporting plate 16. Further, by this arrangement the heating effect is better. If desired, the bottom plate 15 may be attached to the end plate 10 by a suitable plate 17 in order to 80 provide a more sturdy structure, and the lower end of the end plate 11 may be bent inward and attached to the upper end of the plate 15. In a preferred form the plates 15 and 16 are made up in one piece of stamped 85 metal.

Around the sleeve 9 the resistance material 5 is preferably wound. This resistance material may be of any desired type. For purposes of illustration I have shown the 90 same to consist of a single length of helically coiled resistance wire wound upon an insulating sheet 18 inclosing the sleeve 9. In a preferred form the resistance material is so wound around the sleeve 9 that it does 95 not contact with any of the metal parts of the casing at either end of the latter. It is to be noted that this resistance material is housed in the sealed heat retaining chamber 14, so that the heat developed by the 100 same is not readily transmitted to the outside of the casing so that it may be dissipated in the atmosphere.

The door mechanism is preferably located at one end of the chamber 3 and in a preferred form is adapted to close the opening in the end member 11, and is preferably provided with a rounded outer surface 20

adapted to be engaged by the articles or objects to be inserted in the heating chamber. The lower end of the door 8 is preferably provided with extensions 22 swiveled on a 5 rod 21 journaled as at 23 in the opposite sides of the casing. In a preferred form the rod 21 is arranged beneath the chamber 3 and the lower end of the door extends through a suitable opening 24 in the sleeve 9. A link 25 is preferably arranged to move with the depending end of the door when the door is moved about its pivot, and is preferably connected through any suitable connecting means to the snap switch mechanism 7, preferably carried on the base beneath the casing. If desired, this connection may be made through a second insulating link 26 and a wire 27 extending through an opening 28 in the bottom plate 15 and an opening 29 in a vertically extending plate 30, which serves to position the switch mechanism against an extension 31 on the front plate 16.

The switch mechanism may be made of 25 any desired type adapted to make or break the circuit with a quick snap action. In a preferred form I employ a switch mechanism of the type described in the patent of Charles J. Klein, No. 985,421, filed Sept. 6, 1907, wherein a reciprocating cam member 32 in the form of double frustum, positioned base to base, is reciprocated to cause a garter spring 33, through which the cam member moves, to throw a movable contactor 34 to the opposite limits of its travel to make or break the circuit at contacts 35 with a quick snap action. In a preferred form the switch mechanism is inclosed in a casing 36 between insulating bases 37, and the 30 cam member 32 is provided with the spindle 38, which extends through a suitable opening in the plate 30 toward the back of the casing, where it passes through a suitable opening in a depending plate 39. In a 35 preferred form the free end of the spindle 38 is surrounded by a helical spring 40 and carries on one of its ends a fixed collar 41, which is attached to the wire 27 by any suitable means. If desired, a guiding stud 42 carried on the frame 1 may be used to 40 guide the wire 27 in its movement.

In Fig. 3 I have illustrated a diagram of 45 one form of circuit connections for the heater, the mechanical parts of the device being only roughly indicated and referred to by the same reference numerals as in the previous description. The heating coil 5 for the heater is, as therein shown, preferably arranged in series with the line, and the 50 contactor 34 is arranged to make or break the circuit of this heating coil at the contacts 35 when the door 8 is actuated. Thus it is seen that when the object to be heated is inserted in the heating chamber the door 55 8 is actuated to swing it to the left about

its pivot, with the result of pulling the wire 27 upward and drawing the collar 41 to the right. The movement of this collar 41 against the spring 40 carries with it the spindle 38 and the cam member 32. When 70 the cam member 32 passes through the garter spring 33 the contactor 34 is thrown to the opposite limit of its travel beyond the opposite slope of the cam with a very quick snap action and makes the circuit of the device at the contacts 35. Conversely, when the object to be heated is withdrawn from the heating chamber the circuit of the heating coil 5 is broken, so that the control of the heat supply to the heating chamber is 75 automatic, and no current is flowing in the device except when an object to be heated is 80 within the same.

By my improved construction I have provided an exceedingly simple heating device, 85 in which the current supply is automatically controlled by the insertion or removal of the device to be heated. The heating unit is further inclosed in a chamber which serves to conserve and concentrate the heat about the heating chamber and prevent the loss of heat by radiation. Further, the parts are effectually insulated so that there is no danger of short circuiting. The operation of the snap switch mechanism is such as to 90 make or break the circuit very quickly. Further, the construction is a very rugged one, in which the parts are amply protected and are so arranged as to withstand long 95 use and service. Further, the device may be made up in such a light form that it may be readily carried about, and presents a very neat and pleasing appearance.

While I have in this application described one specific form which my invention may 100 assume in practice, I do not wish to be limited to this form chosen for purposes of illustration, but wish rather to include within the scope of this application all of those forms of my invention falling within its 110 spirit.

What I claim as new and desire to secure by Letters Patent is:—

1. In an electric heating device, a heating coil, and means actuated by an object to 110 be heated and independent of the rate of movement thereof for changing the circuit connections of said coil with a quick snap action.

2. In an electric heating device, a casing 120 having a chamber therein, a heating coil for said chamber, means for closing said chamber, and means rendered operative by an object to be heated but actuated independently thereof for changing the circuit connections 125 for said coil with a quick snap action.

3. In an electric heating device, a frame, a hollow heating coil mounted therein, means normally closing an opening in one 130 end of said coil, and a snap switch mecha-

- nism operated upon movement of said closing means to change the circuit connections of said coil with a quick snap action.
4. In an electric heating device, a frame, 5 a sleeve member supported between the end members of said frame, a heating coil wound around said sleeve and insulated therefrom, said heating coil being inclosed in a sealed chamber, means normally closing 10 one end of said sleeve and means actuated upon movement of an object to be heated for making or breaking the circuit connections of said coil with a quick snap action.
5. In an electric heating device, a frame, 15 a heating coil carried thereby, a sleeve inclosed within said coil and insulated therefrom, a door normally closing one end of said sleeve, a snap switch mechanism carried by said frame and means including link 20 members connecting said door and switch mechanism for changing the circuit connections of said coil with a quick snap action upon movement of said door.
6. In an electric heating device, a metallic 25 casing, a heating coil carried therein, a metal sleeve inclosed in said coil and insulated therefrom, one end of said sleeve being closed by said casing, and said coil being in-

closed in a sealed chamber, a door normally closing the other end of said sleeve, a snap 30 switch mechanism carried by said casing beneath said coil, and means including a flexible connection for actuating said switch mechanism with a quick snap action when said door is moved. 35

7. In an electric heating device, a substantially horizontal base, a frame carried thereon and disposed at an angle with respect thereto, said frame having a chamber formed therein, a heating coil surrounding 40 said chamber, a door closing one end of said chamber, a snap switch mechanism housed between said frame and said base, and operative connections between said door and said snap switch mechanism for changing 45 the circuit connections of said coil with a quick snap action when an object to be heated is inserted in or removed from said chamber.

In witness whereof, I have hereunto subscribed my name in the presence of two witnesses.

HARRY W. DENHARD.
